UNITED STATES PATENT OFFICE.

ROBERT A. LEAGUE, OF GREENVILLE, SOUTH CAROLINA.

PRICE-TAG HOLDER AND ATTACHING DEVICE.

Application filed May 7, 1927. Serial No. 189,651.

My present invention has reference to a simple, novel and thoroughly practical means for removably supporting price tags upon packed commodities and the like.

5 An object is the provision of a device for this purpose in which a flat plate has on its edges guideways for the reception of a removable price tag and has secured on its inner face oppositely curved arms or jaw members which are spring influenced toward each other so that the same will effectively grip the container of the commodity whose selling price is disclosed by the tag on the plate.

15 To the attainment of the above broadly stated objects and others which will present themselves as the nature of the invention is better understood, the improvement also resides in certain other novel features of construction, combination and operative association of parts, one satisfactory embodiment of which is disclosed by the accompanying drawings.

In the drawings:

25 Figure 1 is a side elevation of the improvement in applied position.

Figure 2 is a top plan view thereof.

Figure 3 is a detail sectional view approximately on the line 3—3 of Figure 1.

30 Figure 4 is a perspective view of the improvement looking toward the inner face thereof.

My improvement is designed to be clamped on a round can that provides a commodity holder or upon any other support which is round in cross section. It will be noted as the description progresses that the improvement may be successfully attached to supports of different types which are of varying cross sectional diameters.

45 In carrying out my invention I make use of a flat preferably metal plate 1. I bend the lower edge of this plate upwardly over the face thereof, as at 2. The flange 2 is spaced a slight distance from the plate. The corners of the plate 1, opposite that provided with the guide flange 2 is formed with other guide flanges 3. It will be apparent that a price card 4 may be inserted between the guide flanges 2 and 3 and the plate 1

and effectively held in place by frictional engagement exerted thereagainst by the said guide flanges. Also by providing a space between the guide flanges 3 at the top of the plate the price card may be easily moved off 55 of the said plate and replaced by another price card.

The edges of the plate, at the corners thereof provided with the guide flange 2, are formed with extensions which are rounded 60 over the inner face of the plate and form what I will term ears 5.

The guide flanges 3 are formed by slitting the plate 1 and bending the outer portions of the slits. The portion arranged 65 centrally between the slits is bent over the back of the plate to provide a comparatively long eye or ear member 6. Received in this ear or eye 6 there is a wire member 7. The wire member has its ends bent angularly in 70 a downward direction, as at 8, and these portions 8 have their ends bent upon themselves and extended at an upward and inward angle or toward the part 7 of the wire, as indicated by the numerals 9. The portions of 75 the arms 8 and 9 which are bent upon themselves are received in the ears 5 and the arms 9 have their outer portions bent right- angularly and arched or rounded, as at 10. The rounded portions 10 provide the jaws 80 of the improvement. The wire is constructed of spring metal and consequently the jaws will exert a pressure toward each other, to more effectively bring the jaws 10 toward each other. The said jaws at their 85 junctures with the arms 9 are connected together by the ends of a coil spring 11.

My improvement is of an extremely simple nature, may be cheaply manufactured and readily attached to and secured on any cross 90 sectionally rounded support.

Having described the invention, I claim:

A price card holder comprising a plate having one of its edges adjacent to its ends slit, and the portions of the plate, outward 95 of the slits bent over the faces of the plate to provide guide flanges, said plate having a lower guide flange, the portion of the plate between the mentioned slits being bent over the back of the plate to provide an eye, ears 100

on the inner face of the plate adjacent to the lower corners thereof, a spring wire member received through the eye and having angle arms which are bent upon themselves to provide outer arms and which are received between the ears, said last mentioned arms being inclined toward each other

and merging into right angularly arranged rearwardly extending round jaws which exert a pressure toward each other and a spring connected to the jaws for urging the same toward each other. 10

In testimony whereof I affix my signature.
ROBERT A. LEAGUE.
